WINDOW SCREEN

Albert E. Davis, New York, N. Y.

Application January 12, 1939, Serial No. 250,616

2 Claims. (Cl. 98—99)

The present invention relates to new and useful improvements in window screens and has for its primary object to provide, in a manner as hereinafter set forth, a device of this character comprising a construction and arrangement which is such as to permit the free passage of air while at the same time assuring maximum privacy to the occupants of a house or other building.

10 Other objects of the invention are to provide a screen of the aforementioned character which will be comparatively simple in construction, strong, durable, highly attractive in appearance and which may be manufactured at low cost.

15 All of the foregoing and still further objects and advantages of the invention will become apparent from a study of the following specification, taken in connection with the accompanying drawing wherein like characters of reference designate corresponding parts throughout the several views, and wherein:

Figure 1 is a front perspective view, showing a screen constructed in accordance with the present invention installed.

25 Figure 2 is a perspective view of the device.

Figure 3 is a top plan view.

Referring now to the drawing in detail, it will be seen that the embodiment of the invention which has been illustrated comprises an arcuate 30 panel or the like 1 which may be of any suitable material. Formed integrally with the ends of the panel 1 are what may be referred to as flaps 2. The flaps 2 are engageable with the vertical side walls 3 of a window which is designated generally by the reference numeral 4.

35 Attention is here invited to the fact that the device is installed on the inside of the building. The end portions of the arcuate panel 1 and the flaps 2 are adapted to rest on the sill 5 of the window 4. The reference numeral 6 designates a portion of a building wall.

Depending from the panel 1 is an integral extension 7 the lower end of which is adapted to rest on the floor. Of course, the extension 7 is also arcuate in horizontal section. It will be noted that the vertical edges of the extension 7 are spaced from the flaps 2.

It will thus be seen that a screen has been provided which, when the lower sash 8 of the window

4 is open, will permit free passage or circulation of air but which will effectively obstruct the view into the building from the outside thereof. In addition to assisting in supporting the panel 1, the extension 7 functions as a shield for substantially concealing from view the usual radiator which is installed beneath the window sill 5. The device may be attractively ornamented to enhance the appearance thereof or, if desired, it may carry advertising matter, particularly on its outer surface. If necessary or desirable, any suitable means may be utilized for securing the screen in position in the window. Attention is also called to the fact that the construction of the screen is such that it will not interfere with the functioning of shades, Venetian blinds, curtains, etc.

It is believed that the many advantages of a window screen construction in accordance with the present invention will be readily understood and although a preferred embodiment of the device is as illustrated and described, it is to be understood that changes in the details of construction may be resorted to which will fall within the scope of the invention as claimed.

What is claimed is:

1. An indoor window screen comprising an arcuate panel adapted to be supported in a vertical position on a window sill, the intermediate portion of said panel protruding inwardly beyond the sill, flaps on the ends of said panel extending therefrom into the window opening and being engageable with the lower portions of the vertical side walls of the window opening, and an arcuate extension extending downwardly from the protruding intermediate portion of the panel and constituting a radiator shield.

2. An indoor window screen comprising an arcuate panel adapted to be supported in a vertical position on a window sill, integral flaps on the ends of said panel adapted to extend into the window opening and being engageable with lower portions of the vertical side walls of the window openings, and an arcuate, integral extension extending downwardly from the panel to the floor of the room in which the window opening is formed, said extension having its vertical edges spaced from the flaps.

ALBERT E. DAVIS.
